UNITED STATES PATENT OFFICE

2,101,670

RADIO FREQUENCY AMPLIFIER

Maurice Byk and Jehan de Mare, Paris, France,
assignors to General Electric Company, a corporation of New York

Application October 26, 1934, Serial No. 750,192
In France October 27, 1933

4 Claims. (Cl. 250—20)

Our present invention relates to radio frequency amplifier systems and particularly to amplifiers for superheterodyne radio receivers, and it describes the means which permit increasing the selectivity of such receivers and protecting them against any undesired signal which has the same frequency as that to which one or more elements of the receiver are tuned intentionally. In superheterodyne receivers a kind of interference occurs, which is due to the fact that undesired signals, which have the same frequency as that to which the medium-frequency amplifier is tuned, traverse the selector circuits preceding the frequency-changing system. Several arrangements have been proposed to eliminate this interference. One of these comprises, for example, an antiresonating circuit in series with the antenna, or a resonating circuit between the antenna and the ground, which circuits are adjusted in accordance with the value of the intermediate frequency. Unfortunately these solutions are in general of little effectiveness, and the auxiliary circuits which they constitute introduce, in the tuning circuits, inductive or capacitive components which are variable with the frequency; all of which complicates considerably the problem of single control.

The present invention has for one of its objects to produce, prior to the frequency changing, a considerable attenuation of the signals which are transmitted on the same frequency as that for which the intermediate-frequency amplifier is adjusted. A further object of the invention is to provide such means, which do not introduce disturbances in the adjustment of the circuits and in the operation of the receiver within the wave-band to be received. The invention consists in inserting, between the cathode and the point, which the grid and plate circuits have in common, of the tube or tubes preceding the frequency changer, an impedance, or a system of impedances, whose value passes through a maximum at the value of the intermediate frequency. This impedance, or system of impedances, gives rise to an attenuation, or decrease in amplification, of the frequencies at which this impedance has its maximum value.

Thus a further object of our invention is to provide an amplifier which satisfactorily amplifies the signals to be received and which at the same time produces large attenuation of currents of the undesired frequency.

The novel features which we believe to be characteristic of our invention are set forth with particularity in the appended claims. Our inven-

tion itself, however, both as to its organization and method of operation will best be understood by reference to the following description taken in connection with the accompanying drawing in which Fig. 1 represents a circuit embodying our invention; Fig. 2 shows a modification thereof, and Fig. 3 illustrates certain characteristics of the operation of the circuits of Figs. 1 and 2.

In Fig. 1 the antenna-ground system comprises a primary 1, which is coupled to the secondary 2, 10 which secondary is tuned by means of condenser 3 to the frequency to be received. This condenser is, of course, variable over any desired range of frequencies. The oscillating circuit 2—3 is connected between the cathode 5 and grid 6 of a pentode 4, which is a high-frequency amplifier of the radio receiver. The circuit of plate 9 is coupled to the input of a superheterodyne type of radio receiver 16 by means of the transformer 10, 11. For simplicity's sake the superheterodyne receiver has been indicated by a rectangle. It will, of course, be understood that this receiver comprises the usual local heterodyne oscillator and first detector whereby the intermediate frequency oscillations are produced, which intermediate frequency oscillations are amplified and detected in subsequent portions, not shown, of the receiver. The cathode 5 is connected to a point, which is common to the grid and plate circuits, through the antiresonating circuit 12, 13 provided in accordance with our invention, and which is tuned to the intermediate frequency. A resistance 14, which is shunted by a capacitance 15 serves to establish the polarization of the grid in the known manner. It goes without saying that several stages, such as the one which has been described, may be used in cascade, and that the simple oscillating circuit 12, 13 may be constituted by any desirable system of impedance having a high impedance for the intermediate frequency.

It will be understood, further, that the invention is not limited to the type of tube represented in Fig. 1. It is applicable to any other amplifying tube and particularly to the multigrid tubes 45 which comprise, besides the grids 6, 7 and 8 shown on that figure, additional grids which serve, either to confer to that tube the combination role of amplifier and frequency changer, or to regulate the amplification. In such circuits 50 the antiresonant filter circuit is best placed in that branch of the circuit which the anode (which may be in the form of a grid acting as an anode), and the grid, which receives the signal impulses, have in common.

In Fig. 1, the suppressor grid 8, which is utilized to avoid the return of the secondary electrons emitted by the plate, is connected directly to the cathode. In Fig. 2, which constitutes likewise a 5 very simplified scheme of the invention, the grid 8, which has the same purpose as in circuit 1, is connected between the protecting circuits 12, 13 (or the system of impedances which is intended to replace it), and the resistance 14 which is 10 shunted by the capacitance 15. It may be connected directly to the point which the cathode-grid-plate circuits have in common, in the case where this shunted resistance is not included in the circuit.

15 Fig. 3 represents curves which give the attenuation produced by the arrangements that have been described. Curve *a* relates to the circuit of Fig. 2, and curve *b* relates to the circuit of Fig. 1. The attenuation curves express the relation 20 between the frequency transmitted and the attenuation in decibels. The frequency has been plotted as abscissas and attenuation as ordinates. The vertical dot and dash line corresponds to the intermediate frequency to which, in turn, the 25 maximum attenuation corresponds. It will be observed that considerably greater attenuation is obtained from the circuit of Fig. 2 from that obtained from the circuit of Fig. 1.

While we have shown particular embodiments 30 of our invention, it will of course be understood that we do not wish to be limited thereto since different modifications may be made, and we therefore contemplate by the appended claims to cover any such modifications as fall within the 35 true spirit and scope of our invention.

What we claim as new and desire to secure by Letters Patent of the United States, is:

1. In a superheterodyne radio receiver, an electron discharge amplifier having an anode, a 40 cathode and two grids, the combination of an input circuit connected between said cathode and one of said grids, an output circuit connected between said cathode and anode, a connection between the other of said two grids and said 45 cathode, said other grid being maintained at the potential of said cathode, means to tune said amplifier for operation at a desired frequency, and means to reduce the transfer through said amplifier of energy having a frequency equal to the intermediate frequency of said receiver and 50 received in said circuit between said one grid and said cathode, said means comprising a circuit tuned to said intermediate frequency connected

in a common portion of both of said circuits and said connection.

2. In an electron discharge amplifier having an anode electrode, a cathode, a suppressor grid electrode adjacent to said anode electrode maintained at substantially the unidirectional potential of said cathode and a control grid electrode, the combination of connections between said cathode and each of said electrodes, means to tune said amplifier for operation at a desired 10 frequency and means to reduce the transfer of energy of an undesired frequency from said control grid electrode connection to said anode electrode connection through said discharge device, said means comprising a circuit common to all 15 of said connections said circuit being antiresonant at said undesired frequency.

3. In an electron discharge amplifier having an anode, a cathode, a control grid, a screen grid, and a suppressor grid between said screen grid 20 and said anode, an output circuit between said anode and cathode including a source of operating potential, a bias resistor, and a parallel resonant circuit in the order named, an input circuit between said control grid and said cathode 25 including said bias resistor and said parallel resonant circuit, a screen grid circuit, and a connection between said suppressor grid and a point on said input and output circuits between said bias resistor and said parallel resonant circuit 30 whereby said suppressor grid is maintained at the potential of said cathode except for potentials appearing on said resonant circuit, said resonant circuit being tuned to a frequency the transmission of which through said amplifier is to be 35 reduced.

4. In an electron discharge amplifier having an anode, a cathode, a control grid and a second grid, an output circuit between said anode and cathode, an input circuit between said grid and cathode, a bias resistor common to said input and output circuits, said second grid being connected to the end of said bias resistor nearer the cathode whereby said second grid is maintained at the cathode potential, and means to prevent 40 transmission through said amplifier of currents of a certain frequency, said means comprising a tuned circuit connected in said input and output circuits and between said cathode and said second grid. 45
